UNITED STATES PATENT OFFICE

166,526

BOTTLE OR SIMILAR ARTICLE

John D. Buckingham, Chicago, Ill., assignor to Virginia Parks, Inc., Chicago, Ill., a corporation of Illinois

Application March 1, 1950, Serial No. 8,240

Term of patent 14 years

(Cl. D58—25)

To all whom it may concern:

Be it known that I, John D. Buckingham, a citizen of the United States, residing at Chicago, county of Cook, and State of Illinois, have invented a new, original, and ornamental Design for a Bottle or Similar Article, of which the following is a specification, reference being had to the accompanying drawing, forming a part thereof:

Figure 1 is perspective view of a bottle or similar article embodying my new design;

The dominant feature of my design resides in the random arrangement of various sized beads on the body and cap portions of the bottle.

I claim:

The ornamental design for a bottle or similar article, substantially as shown and described.

JOHN D. BUCKINGHAM.
